DESIGN FOR A SWITCHING DEVICE

Hugh McDowell, Los Angeles, Calif.

Application May 4, 1940, Serial No. 92,170

Term of patent 7 years

To all whom it may concern:

Be it known that I, Hugh McDowell, a citizen of the United States, residing at 8957 Appian Way, in the city of Los Angeles, in the county of Los Angeles and State of California, have invented a new, original, and ornamental Design for a Switching Device, of which the following is a specification, reference being had to the accompanying drawing, forming part thereof, in which

Fig. 1 is a front elevational view of a switching device showing my new design; and Fig. 2 is a top plan view thereof.

I claim:

The ornamental design for a switching device, as shown.

HUGH McDOWELL.
